UNITED STATES PATENT OFFICE

ELMER G. GARTIN, OF CLAREMONT, NEW HAMPSHIRE, ASSIGNOR TO SULLIVAN MACHINERY COMPANY, A CORPORATION OF MASSACHUSETTS

DRILLING APPARATUS

Application filed October 26, 1928. Serial No. 315,327.

My invention relates to drilling apparatus and particularly to retainers for rock drill steels.

It is an object of my invention to provide an improved retainer construction for rock drills. A further object of the invention is to devise an improved drill steel retainer construction which may be easily manufactured. Another object of my invention is to provide an improved construction for drill steel retainers having improved means for holding the retainer in operative or inoperative position. A still further object is to provide improved self-locking means for holding the parts of the retainer in assembled relation. Other objects and advantages of the invention will hereinafter more fully appear.

In the accompanying drawing I have shown for purposes of illustration one form 20 which the invention may assume in practice.

In the drawing,—

Fig. 1 illustrates a side elevational view of the front end of a rock drill having my improved retainer construction associated therewith.

Fig. 2 is an elevation of the rock drill at right angles to the view shown in Fig. 1, with parts shown in section to facilitate illustration.

Fig. 3 is a transverse section on line 3—3 of Fig. 1, with parts broken away to show details of construction.

The rock drill with which I have shown my improved retainer construction associated may be of a well known construction having a chuck housing 1 held in assembled relation with a cylinder 2 by means of side rods 3 which exert a resilient clamping force on the sections of the rock drill through 35 springs 4 to hold the different sections in assembled relation. A well known form of drill steel 5 is loosely mounted in the front end of the chuck housing and is provided with a collar 6 formed integral therewith.

40 The retainer comprises a yoke having side arms 7 and 8 with a U-shaped opening 9 in the front end which is of a size adapted to permit freedom of movement of the drill steel, but prevent the passage of the collar 6.

50 A shoulder 10 is provided adjacent the open-

ing 9 with which the collar on the drill steel engages. A pivoted yoke retainer construction having the features just described is old in the art.

One feature of the present invention is directed to novel means for pivoting this yoke on the chuck housing. In a previous construction the yoke was provided with cylindrical portions which were adapted to be pivotally mounted in arcuate recesses formed in lugs integral with the chuck housing. Now, it has been found in actual practice that the milling of a recess having an arcuate bearing surface in a relatively small detachable member such as the retainer yoke is a much more simple matter than the forming of a recess having a smooth arcuate bearing surface in a lug integral with the chuck housing. Accordingly, the present construction has been devised wherein there is employed a pair of diametrically positioned cylindrical trunnions 11 and 12 on the chuck housing which may be formed with sufficient accuracy by a die forging process without machining. Each of the arms 7 and 8 of the retainer yoke is provided with a semi-cylindrical arcuate recess 13 which is adapted to be held in engagement with the trunnions 11 and 12 in the normal position of the retainer. For this purpose the arms 7 and 8 are formed with inwardly projecting lugs 14 and 15 respectively which are engaged by an annular collar 16 slidably mounted on the chuck housing. The collar 16 is resiliently held against the projections 14 and 15 by means of a coiled spring 17 surrounding the chuck housing and a suitable nut 18 is threaded on the end of the chuck housing for holding the spring and other parts in place. The nut 18 is provided with suitable means such as the holes 19 to receive a wrench for the purpose of adjusting the nut to obtain the desired tension on spring 17.

For the purpose of holding the retainer in operative or inoperative position the lugs 14 and 15 are each provided with flat surfaces 20 and 21, the surfaces 20 being adapted to engage the collar 16 when the retainer is held in inoperative position and the surface 21 being adapted to engage the collar 16 100

when the retainer is in normal operative position.

The improved means for locking the parts of the retainer in assembled relation will now be described. The periphery of the collar 16 has at its opposite sides flat portions 22 shown in Fig. 3 which are adapted to cooperate with the arms 7 and 8 of the retainer yoke to prevent rotation of the collar relative to the housing. This collar also has an integral lug 23 (see Fig. 2) engaging in an arcuate groove 24 in the spring 17 to prevent relative rotation between the spring and collar. A second collar 25 is mounted 15 between the spring and ring 18 and has similar lugs 26 and 27 engaging in suitable arcuate recesses in the forward end of the spring and in the threaded ring respectively. The ring 18 cannot therefore work loose 20 since it is locked against rotation relative to the spring 17 and the spring in turn locked to the chuck housing by lugs 23 and collar 16. The shape of the lugs 26 and 27 is however such as to permit intentional movement 25 of the threaded ring by means of a wrench applied to the ring.

In the use of this device, when it is desired to remove a drill steel, the operator moves the retainer to the dotted line position shown in Fig. 1, the arms 7 and 8 swinging on the pivots 11 and 12 and the compression of spring 17 acting on the collar 16 will resiliently hold the retainer yoke in the position illustrated. When the dull steel 35 has been replaced by a resharpened one, the retainer is swung into full line operative position with the surface 21 bearing on the collar which serves to hold it in operative position. The drill steel is effectively prevented from dropping out of the chuck housing by means of the collar 16 engaging the shoulder 10 on the retainer yoke. If the hammer mechanism of the drill is operated while the drill steel is not bearing against 40 the work, the blow will be transmitted through the collar on the drill steel and the retainer yoke to the spring 17, where it will be effectively cushioned to prevent breakage of the retainer or other parts.

50 While I have in this application specifically described one form which my invention may assume in practice, it will be understood that this form of the same is shown for purposes of illustration and that the invention 55 may be modified and embodied in various other forms without departing from its spirit or the scope of the appended claims.

What I claim as new and desire to secure by Letters Patent is:

60 1. In a rock drill, a chuck housing having cylindrical lugs projecting laterally therefrom, a retainer yoke pivotally mounted on said chuck housing and having arcuate bearing surfaces cooperating with said lugs, and 65 means for resiliently maintaining said bear-

ing surfaces in engagement with said lugs comprising an annular member surrounding said chuck housing and engaging said yoke and yielding means for holding said member against said yoke and for holding said bearing surfaces in contact with said lugs. 70

2. In a rock drill, a chuck housing having cylindrical lugs projecting laterally therefrom, a retainer yoke pivotally mounted on said chuck housing, the arms of said yoke having arcuate bearing surfaces engaging said lugs, and means for resiliently maintaining said bearing surfaces in engagement with said lugs comprising an annular member surrounding said chuck housing and engaging said yoke, a retaining member secured to said chuck housing and a spring interposed between said annular member and said retaining member. 75

3. In a rock drill, a chuck housing having cylindrical trunnions projecting laterally therefrom, a retainer yoke pivotally mounted on said chuck housing and having arcuate bearing surfaces engaging said trunnions, a pair of inwardly directed lugs on the arms of said yoke adjacent said arcuate bearing surfaces, a collar surrounding said chuck housing and engaging said inwardly directed lugs, and means for resiliently holding said collar in engagement with said lugs and said recesses in contact with said trunnions. 80

4. In a rock drill, the construction defined in claim 3 wherein said inwardly projecting lugs are provided with a plurality of flat surfaces in angular relation, said collar adapted to bear against a pair of said surfaces to hold said retainer in operative or in inoperative position. 95

5. In a rock drill, a chuck housing having cylindrical trunnions projecting laterally therefrom, a retainer yoke having spaced arms with rearwardly opening arcuate recesses in the ends of said arms, one of said trunnions being received in each of said recesses, inwardly directed lugs integral with said yoke arms adjacent said bearing surfaces, a collar slidably mounted on said chuck housing and engaging said inwardly directed lugs, a spring surrounding said chuck housing in contact with said collar, and a ring secured on the end of said chuck housing for placing said spring under compression and holding said yoke against said trunnions. 105

6. In a rock drill, a chuck housing having laterally projecting lugs, a drill steel loosely mounted in said chuck housing, a retainer yoke for said drill steel having a pivotal connection to said lugs, means for resiliently holding said yoke against said lugs including a collar surrounding said chuck housing, a spring, a retaining nut threaded on said chuck housing, means for preventing rotation of said collar, and cooperating means 110 120 125 130

on said collar and nut for locking the latter against accidental movement.

7. In a rock drill, a chuck housing having laterally projecting lugs, a drill steel loosely mounted in said chuck housing, a retainer yoke for said steel having means to provide a pivotal connection with said lugs, means for resiliently holding said yoke against said lugs including a retaining nut threaded on the end of said chuck housing, a collar slidably mounted on said chuck housing, yielding means acting upon said retainer yoke and yieldingly holding said collar against said nut, means for locking said collar against rotation, and a cooperating lug and recess on said collar and nut to lock the latter against accidental movement.

8. In a rock drill, a chuck housing having laterally projecting lugs, a drill steel loosely mounted in said chuck housing, a retainer yoke for said steel having means to provide a pivotal connection with said lugs, means for resiliently holding said yoke against said lugs including a retaining nut threaded on the end of said chuck housing, a spring surrounding the chuck housing between said nut and said lugs, means for preventing relative rotation between said spring and said chuck housing, and means for locking said nut to said spring to prevent accidental movement of said nut.

9. In a rock drill, a chuck housing having laterally projecting lugs, a drill steel loosely mounted in said chuck housing, a retainer yoke for said drill steel having a pivotal connection to said lugs, means for resiliently holding said yoke against said lugs including a collar surrounding said chuck housing, a spring, a retaining element secured on said chuck housing, means for preventing rotation of said collar, and cooperating means on said collar and retaining element for locking the latter against accidental movement.

10. In a rock drill, a chuck housing having laterally projecting lugs, a drill steel loosely mounted in said chuck housing, a retainer yoke for said steel having means to provide a pivotal connection with said lugs, means for resiliently holding said yoke against said lugs including a retaining element secured on the end of said chuck housing, a collar slidably mounted on said chuck housing, yielding means acting upon said retainer yoke and yieldingly holding said collar against said retaining element, means for locking said collar against rotation, and a cooperating lug and recess on said collar and retaining element to lock the latter against accidental movement.

11. In a rock drill, a chuck housing having laterally projecting lugs, a drill steel loosely mounted in said chuck housing, a retainer yoke for said steel having means to provide a pivotal connection with said lugs, means for resiliently holding said yoke

against said lugs including a retaining element secured on the end of said chuck housing, a spring surrounding the chuck housing between said retaining element and said lugs, means for preventing relative rotation between said spring and said chuck housing, and means for locking said retaining element to said spring to prevent accidental movement of said retaining element.

In testimony whereof I affix my signature. 75
